UNITED STATES PATENT OFFICE.

THOMAS H. AINSWORTH, OF SCHENECTADY, NEW YORK.

LOCOMOTIVE TRUCK.

Application filed August 19, 1926. Serial No. 130,189.

My invention relates to trucks equipped with lateral motion appliances, and its object is to provide means for taking up the wear incident to the oscillation of the rockers employed to permit of lateral movement of the wheels.

The improvement claimed is hereinafter fully set forth.

In the accompanying drawing: Figure 1 is a plan or top view of a truck embodying my improvement; Fig. 2, a view, the left hand half of which is a vertical transverse section, on the line *a a* of Fig. 1, and the right hand half, an end elevation; Fig. 3, a half horizontal transverse section, on an enlarged scale, through the rocker seat plate; and, Fig. 4, a half vertical transverse section through the same.

It is well known in the art to employ substantially heart shaped rockers to permit of lateral movement of the wheels. Such rockers are customarily provided, at their bottoms, with two substantially cylindrical ears, which fit in correspondingly shaped grooves in the rocker seat plate. Due to the great weight borne by the rockers, and their frequent oscillation, considerable wear of both the rocker and seat, occurs in service. This invention is primarily directed to providing means for taking up the wear incident to the oscillation of the rockers.

In the practice of my invention, referring descriptively to the specific embodiment

thereof which is herein exemplified, my invention is applied in a truck, the wheels, 1, 35 axle, 2, journal boxes, 3, and frame, 4, of which are all of the usual construction. The frame embodies a rocker seat plate, 5, having seat grooves, 6, in which are seated the two ears, 7, of the heart shaped rockers, 8. 40

For the purpose of taking up the wear incident to the oscillation of the rockers, I provide a renewable curved bushing, 9, in each seat groove, 6. The bushings, 9, may be welded, or otherwise secured to the seats, and it is within the contemplation of the invention to apply the bushings directly to the ears of the rockers. 45

Heretofore, in the art, frequent renewal of the bearing plates has been necessary, due to 50 the wear on the seat grooves incident to the oscillation of the rocker. My improvement provides means adapted to take up the wear incident to the oscillation of the rockers, said means being readily renewable at considerably less expense than is involved in replacing the entire seat plates. 55

I claim as my invention and desire to secure by Letters Patent:

In a truck, the combination of a frame; a 60 rocker, having curved bearing ears; a plate, having curved recesses for the reception of said ears; and curved bushings, fitted in said recesses, and welded to the plate.

THOMAS H. AINSWORTH.
